EXTENSIBLE BUCKLE CONSTRUCTION

Eugen Prestinari, Summit, N. J., assignor to
Gemex Company, Newark, N. J., a corporation
of New Jersey

Application December 5, 1934, Serial No. 756,058

15 Claims. (Cl. 24—71)

This invention relates to an expandable bracelet construction and more particularly to an expandable device to be included in a watch bracelet or the like.

5 One of the objects of this invention is to provide a device of the above character which will be simple, practical, and thoroughly durable. Another object is to provide a device of the above character of ready and inexpensive manufacture. Another object is to provide a device of the above character which 10 has a pleasing appearance. Another object is to provide a device of the above character by which the length of a bracelet may be varied between comparatively wide limits and in which a fine adjustment of the length may, nevertheless, be achieved. Another object is to provide 15 a device of the above character in which it is possible to accomplish a fine adjustment of the length of the bracelet in either direction by the simple and convenient expedient of applying pressure with the finger to one side of the clasp. Another object is to provide a construction of the above character lacking small protruding portions on the sides and top of the clasp whether the clasp be folded or unfolded. 20 Other objects will be in part obvious and in part pointed out hereinafter.

The invention accordingly consists in the features of construction, combination of elements, and arrangement of parts as will be exemplified 25 in the structure to be hereinafter described and the scope of the application of which will be indicated in the following claims.

In the accompanying drawing in which is shown one of the various possible embodiments 30 of my invention,

Figure 1 is a bottom plan view of my device in an open position when associated with or connected to a bracelet or the like;

Figure 2 is a vertical sectional view on an 45 enlarged scale taken along the line 2—2 of Figure 1;

Figure 3 is an enlarged horizontal sectional view of the housing link shown in Figure 1 taken along the line 3—3 of Figure 2; and

50 Figure 4 is a top plan view of another portion of the device shown in Figure 1.

Similar reference characters refer to similar parts throughout the several views of the drawing.

55 As conducive to a clearer understanding of

certain features of this invention, it might here be pointed out that many of the extensible clasps or buckles of this general character have annoying, undesirable and inconvenient characteristics. For example, some of these buckles are provided with projecting parts placed in such positions that they are apt to catch in the cuff or sleeve of the wearer, thus being a constant source of annoyance and tending to rip and otherwise damage clothes. In other 10 clasps of this general character, it is impossible to get a fine adjustment of the length of the bracelet while the links of the clasp are in the extended position and it is necessary to adjust the clasp each time it is placed upon 15 the wrist of the wearer. Furthermore, some of these clasps have an unsightly appearance due to their structure, as, for example, a longitudinal slot appearing in one of the side walls, this slot also tending to catch in the wearer's 20 clothes. One of the objects of this invention is to provide a device of the above character in which the above-mentioned difficulties as well as many others are successfully overcome.

Referring now to Figure 1 in detail, the opposite end links 10 and 11 of a watch bracelet or the like are shown connected to the various parts comprising my expandable clasp. Thus end link 11 is hingedly connected to a sliding link generally indicated at 12, which is slidably 25 mounted within a housing link generally indicated at 13, while the end link 10 is hingedly connected to a link 14 which, in turn, is hingedly connected to a link 15. Link 15 is slidably 30 mounted in a casing link 16 which is hingedly 35 connected to housing link 13, all as will be more fully described hereinafter.

Still referring to Figure 1, a pair of pins 17 and 18 bridge the spaced side portions of links 11 and 12, respectively, preferably being integral parts thereof. Pins 17 and 18 are preferably connected by a clip member 19 extending thereabout to hold the parts in hinged relationship. A pin 20 preferably extends through the sides of link 14 and through an eye portion 45 21 secured thereto and is thence connected at its ends to the sides of link 10 thus forming a hinged connection between end link 10 and link 14.

Referring now to Figures 1 and 2, housing 50 link 13 preferably consists of a top portion 22, side walls 23 and 24, and inwardly extending flanges 25 and 26, thus forming longitudinal channels 27 and 28 in which link 12 is slidably mounted.

55

A frame 29 forming a part of link 12 rests upon top 22 of the housing link 13 and has formed therein a cut-out portion 30. One edge 12a of sliding link 12 preferably lies adjacent side wall 23 and formed thereon a hollow leg portion generally indicated at 75. Thus a pair of vertically disposed flanges 31 and 31a are disposed substantially at the ends of leg portion 75 (Figure 3) and a top flange 33 (Figure 2) extends inwardly from flanges 31 and 31a beneath flange 26 of housing link 13. Accordingly, flanges 31 and 31a together with top flange 33 form leg portion 75 riding within the longitudinal channel 28 of housing link 13. Furthermore, as will be seen from a consideration of Figures 2 and 3, a longitudinal slot 32 is located in the side of leg portion 75 adjacent side wall 23. An upturned lip 20a is provided on top 22 of link 13 and is positioned within the cut-out portion 30 of link 12. Accordingly, the outward movement of link 12 (right hand movement as viewed in Figure 3) is limited by lip 20a.

The opposite side 12b of link 12 extends upwardly, inwardly, and thence downwardly (Figure 2) to form, in effect, a leg portion 34 slidably fitting within the longitudinal channel 27. Preferably, the dimensions of the sliding link 12 and housing link 13 are so proportioned that little relative movement in lateral directions exists therebetween although the parts are perfectly free to move longitudinally with respect to each other.

As best shown in Figures 2 and 3, an arm 35 preferably resilient in character is located within leg portion 75 one end thereof being desirably connected to flange 31. Accordingly arm 35 is free to move in lateral directions within leg portion 75 toward and away from slot 32 and substantially about its point of connection with flange 31. A plurality of ratchet teeth 36 are cut or otherwise formed in the edge of resilient arm 35 adjacent slot 32 and have edges 37 at right angles to side wall 31 and edges 38 at acute angles to the same wall. The extremities of ratchet teeth 36 preferably extend into longitudinal slot 32. A finger piece 39 preferably forming a part of the free end of arm 35 extends through slot 32 to a point spaced from the outside face of wall 23 (Figure 3). Accordingly, arm 35 and teeth 36 move away from slot 32 when pressure is applied to finger piece 39.

Referring now to Figure 3, a pawl 40 is preferably formed on side wall 23 by bending a piece 55 of the side wall inwardly so that it extends within slot 32 to engage ratchet teeth 36 when arm 35 is in its normal position, the resiliency of arm 35 tending to hold the parts in this engaging relationship. The end 40a of pawl 40 is preferably beveled and parallel to edges 38 of teeth 36. Accordingly when sliding link 12 is pushed in a left hand direction as viewed in Figure 3, teeth 36 ride over pawl 40 but attempted movement of link 12 in a right hand direction as viewed in this figure is prevented by the engagement of one edge 37 of the teeth with the flat side of the pawl. However, by pressing the finger piece inwardly the ratchet teeth and the pawl are disengaged and the wearer will be able to move the sliding link in either direction with ease.

Referring to Figure 3, housing link 13 has a pin 42 extending through side walls 23 and 24 75 and bridging the space therebetween; casing

link 16 has an eye portion 43 which fits about pin 42. As more clearly shown in Figure 1, link 16 is narrower than the distance between inwardly extending flanges 25 and 26 of housing link 13 and consequently link 16 may be folded over into nested position between these flanges. 5

Referring now to Figure 4, casing link 16 comprises bottom portion 16a, side walls 16b and 16c, and inwardly extending flanges 44 and 45 forming a longitudinal slot 76 closed at the end remote from link 13 by a part 47. Sliding link 15 fits within casing link 16 and its extending movement therein is limited by a lug 46 mounted on the end portion thereof nearest the housing link 15 and extending into slot 76. 10

Still referring to Figure 1, link 15 preferably has an eye portion 49 fitting about a pin 50 secured to link 14 thus forming a hinged connection between links 14 and 15. Link 14 is provided with side walls 53 and 54 sufficiently spaced from each other to allow link 16 to fit therebetween. Accordingly, it will now be clear that link 15 may slide within casing link 16 after which link 16 may pivot about pin 42 and link 14 may pivot about pin 15 until link 16 rests within housing link 13. In this position link 14 fits over link 16 having its side walls 53 and 54 resting between the inwardly extending flanges 26 and 25 of housing link 13 and the side walls 16b and 16c of casing link 16. 20 In this nested position, links 14, 15, and 16 are effectively contained within the housing link and the bottom portion 14a together with flanges 25 and 26 form the bottom side of the buckle. Furthermore, when in this position, links 14, 15, and 16 do not interfere with the extending and contracting movement of sliding link 12 as has been more fully described above. 30

On sides 53 and 54 of link 14 there are a pair of projections 55 and 56 which snap past or catch under the edges of flanges 25 and 26 of housing link 13. Thus when links 14, 15, and 16 are folded into the nested relationship within the housing link 13, they are held in this position against accidental displacement by projections 55 and 56. Preferably to disengage these projections from the flanges 25 and 26, I provide a flange 48 (Figure 4) projecting from the top portion of link 13. This affords means of lifting housing 13 up from links 14, 15, and 16 when the device is in position on the wrist of the wearer. 40

A bracelet having my extensible buckle applied thereto may be slipped over the hand of the wearer into position on the wrist while links 14, 15, and 16 are in the extended position shown in Figure 1. Next sliding link 15 may be moved into position within folding link 16 after which housing link 13 may be brought down upon links 16 and 14 to bring these links into a nested position within the housing link. Projections 55 and 56 snap under flanges 25 and 26 to hold the links in this nested position and the length of the bracelet may be further adjusted by pushing link 12 into housing link 13. If a bracelet of greater length is desired, it is merely necessary to apply pressure to finger piece 39 which, as described more fully above, allows link 12 to slide in either direction. After the desired length of the bracelet has been achieved, the bracelet may be removed from or placed upon the wrist at will without readjusting its length. However, should the wearer desire a readjustment of length, it may be accomplished regard- 70 75 80 85 90 95 98 99 100

less of the position of folding links 14 and 16 with respect to the housing link 13.

It will thus be seen that I have provided a thoroughly practical and efficient construction and method in which the several objects hereinabove referred to, as well as many others, are successfully and practically accomplished.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

15 I claim:

1. In an extensible buckle, in combination, a housing link having a top portion, side walls, and flanges extending inwardly forming longitudinal channels, a pawl on one of said side walls, a link slidably mounted in said housing link, said sliding link having a resilient arm fastened at one end to said sliding link adjacent one of the side walls of said housing link, said resilient arm having a plurality of ratchet teeth formed thereon in engagement with said pawl, and a finger piece attached to said resilient arm and extending outwardly to a point beyond one of said side walls.

2. In an extensible buckle, in combination, a housing link having a top portion, side walls and inwardly extending flanges forming longitudinal channels, a pawl on said housing link, a link slidably mounted in said housing link, a member movably secured to said sliding link, a plurality of ratchet teeth on said member, said ratchet teeth being in engagement with said pawl.

3. In an extensible buckle, in combination, a housing link member, said housing link member having a top portion, side walls and portions extending inwardly from said side walls, a pawl on one of said side walls of said housing link member, a link member slidably mounted in said housing link member, a resilient arm on said sliding link member covered by one of said inwardly extending portions, a plurality of ratchet teeth on said arm engaging said pawl, a finger piece attached to said arm, and a plurality of link parts hingedly connected to each other and hingedly connected to one of said link members to fold into a nested position between and engage said inwardly extending portions of said housing link member whereby said link parts are out of engagement with said pawl, said arm and said ratchet teeth.

4. In an extensible buckle, in combination, a housing link having a top portion and side walls, a pawl extending from one of said side walls, and a link slidably mounted in said housing link between said side walls, said sliding link having a top portion and sides, the side of said sliding link adjacent said pawl having a slot therein, an arm fastened to said sliding link and including a portion extending through said slot, a plurality of ratchet teeth on said arm adjacent said slot and positioned to engage said pawl, and means for moving said arm to disengage said teeth and said pawl.

5. In an extensible buckle, in combination, a housing link member having a top portion and side walls, a link slidably mounted in said housing link, said sliding link having sides, one of said sides of said sliding link having a longitudinal slot therein, an arm member connected to said sliding link adjacent said slot, a plurality of ratchet teeth on one of said members said

ratchet teeth being nearer the slotted side of said sliding link than the other side thereof, a pawl on the other of said members positioned to engage said teeth, and a finger piece attached to said arm member substantially at one end 5 thereof and extending through said slot.

6. In an extensible buckle, in combination, a housing link having a top portion and side walls, a link slidably mounted in said housing link, a pawl on one of said links, said sliding link having a top portion and sides, one of said sides having a slot therein, an arm member movably secured to the other of said links and having a portion extending through said slot, a plurality of ratchet teeth on said arm member, said arm 15 being resilient to engage said ratchet teeth and said pawl.

7. In an extensible buckle, in combination, a housing link having a top portion and side walls, a pawl on one of said side walls of said housing 20 link, a link slidably mounted on said housing link, said sliding link having a top portion and sides, one of said sides having a slot therein, an arm member movably secured to said sliding link, a plurality of ratchet teeth on said arm member, 25 and a finger piece attached to said arm member substantially at one end thereof and extending outwardly through said slot to a point beyond one of said walls of said housing link.

8. In an extensible buckle, in combination, a 30 housing link member, said housing link member having a top portion, side walls, and portions extending inwardly from said side walls, a pawl on one of said side walls of said housing link member, a link member slidably mounted in said 35 housing link member, a resilient arm on said sliding link member covered by one of said inwardly extending portions, a plurality of ratchet teeth on said arm engaging said pawl, a finger piece attached to said arm, and a plurality of 40 link parts hingedly connected to each other and hingedly connected to one of said link members to fold into a nested position between and engaging said inwardly extending portions of said housing link whereby said link parts are out of engagement with said pawl, said arm and said 45 ratchet teeth.

9. In an extensible buckle, in combination, a housing link member including a top portion and side wall portions extending therefrom, a link 50 member slidably mounted in said housing link member, said sliding link member including side wall portions registering with the side wall portions of said housing link member and being guided thereby when said link members are telescoped together, one of said link members having bottom portions extending toward one another in a plane substantially parallel to the plane of said top portion of said housing link member, said sliding link member having a longitudinal slot formed in one of its side wall portions, means forming a plurality of ratchet teeth extending into said slot, said means being movable with said sliding link member, a pawl member related to said housing link member and adapted to engage said ratchet to prevent relative movement between said link members, a finger piece extending through said longitudinal slot and related to one of said link members, said finger piece being movable transversely of 60 said link members to disengage said pawl member and said ratchet whereby the relative positions of said link members may be varied at will.

10. In an extensible buckle, in combination, a housing link member including a top portion and 75

side wall portions extending therefrom, a link member slidably mounted in said housing link member, said sliding link member including side wall portions registering with the side wall portions of said housing link member and being guided thereby when said link members are telescoped together, said sliding link member having a longitudinal slot formed in one of its side wall portions, means forming a plurality of ratchet teeth extending into said slot, said means being movable with said sliding link member, a pawl member related to said housing link member and adapted to engage said ratchet teeth to prevent relative movement between said link members, a finger piece extending through said longitudinal slot and related to one of said link members, said finger piece being movable transversely of said link members to disengage said pawl member and said ratchet whereby the relative positions of said link members may be varied at will.

11. In an extensible buckle, in combination, a housing link member including a top portion and side wall portions extending therefrom, a sliding link member telescopically related to said housing link member and having side wall portions registering with the side wall portions of said housing link member, said sliding link member having a longitudinal slot formed in one of its side wall portions, a resilient arm secured to the slotted side wall of said sliding link and having ratchet teeth formed thereon, a pawl member related to said housing link member adapted to engage said ratchet teeth to prevent relative movement between said link members, and a finger piece secured to said arm and extending through said longitudinal slot, said finger piece being movable to disengage said ratchet teeth from said pawl member.

12. In an extensible buckle, in combination, a housing link member having a top portion and a pair of channels formed along the sides thereof, a link slidably mounted in said housing link member and having a pair of channels formed along the longitudinal sides thereof and adapted to fit within the longitudinal channels formed upon said housing link, an arm member mounted in one of the channels of said sliding link, a pawl mounted upon one of said members, and a plurality of ratchet teeth mounted upon the other of said members, said arm being resilient to engage said ratchet teeth and said pawl.

13. In an extensible buckle, in combination, a housing link having a top section and at least one longitudinal side portion, a link slidably

mounted on said housing link, said sliding link including an arm portion, a pawl on one of said portions, a plurality of ratchet teeth on the other of said portions, said arm portion being capable of transverse movement with respect to said side portion to engage and disengage said teeth and said pawl, and a finger piece on said arm portion spaced from and free of said housing link when said sliding link is extended therefrom.

14. In an extensible buckle, in combination, a housing link having a top portion and longitudinal side walls, a pawl on one of said side walls and extending inwardly therefrom, means forming a link slidably mounted in said housing link, said means including an arm member, and a plurality of ratchet teeth on said arm member adjacent said pawl, said arm member being capable of transverse movement with respect to said side walls to engage and disengage said pawl and said ratchet teeth, and a finger piece on said arm portion spaced from and free of said housing link when said sliding link is extended therefrom.

15. In an extensible buckle, in combination, a housing link having a top portion, side walls along the longitudinal edges thereof and portions extending inwardly toward each other from said side walls and underlying said top portion, said side walls and underlying portions forming with said top portion longitudinal channels, means forming a sliding link adapted to slide within said housing link, said means including substantially parallel side parts connected together at at least one end thereof and respectively movably disposed for longitudinal reciprocation within said channels, at least one of said parts being resiliently movable toward and away from the other of said parts, a pawl on that one of said housing link side walls adjacent said resilient part, said pawl extending inwardly of said housing link, a plurality of ratchet teeth formed on said resilient part and positioned for ratcheting engagement with said pawl during movement of said sliding link into said housing link, and a finger piece secured to said resilient part and extending outwardly therefrom, said finger piece being positioned for inward pressure thereof whereby said ratchet teeth on said resilient part are moved inwardly away from said pawl to permit free extension of said sliding link from within said housing link, said finger piece being spaced from and free of said housing link when said sliding link is extended therefrom.

EUGEN PRESTINARI.
